Daniel Pittibone

1921X

specifications of a method of flattening say this Houghines and
many other thin slate tools to discover by me Daniel Pittibone
as follows. Next, — I weld the bed of iron & to it let together
as usual in the common way. (left iron will be found to make
the junction) and then make it to an exact thickness of plate by
means of a tilt or hand however or a rolling mill — except
a small notch at one end and for the back or crank: to fasten
it to the foundation the plate is made the back is formed (so as
to give it near double the strength) with mould stamps, swages, or any
other method to give it form and form a double back as the
model.
